FUSE PLUG

Milo M. Culbert, Caro, Mich.

Application July 27, 1935, Serial No. 33,584

2 Claims. (Cl. 200—130)

This invention appertains to new and useful improvements in fuse plugs.

The principal object of the invention is to provide a fuse plug constructed in such a manner as 5 to permit quick insertion into a fuse socket.

Another important object of the invention is to provide a fuse plug involving construction whereby the fuse will be thrown from its socket upon the rupturing of its fusible elements.

10 These and various other important objects of the invention will become apparent to the reader of the following specification.

In the drawings:

Figure 1 represents a sectional view through a 15 fuse socket showing the fuse installed therein.

Figure 2 represents a front elevational view of the fuse plug.

Figure 3 is a top plan view of the plug.

20 Figure 4 represents a side elevational view of the plug.

Figure 5 represents an enlarged longitudinal sectional view of the plug.

25 Figure 6 represents a fragmentary perspective view of the detent for the fusible element.

Figure 7 represents a perspective view of the fusible element.

30 Referring to the drawings wherein like numerals designate like parts, it can be seen that the plug includes a cylindrical shaped body 5 of insulating material, the same having a fuse pocket 6 formed therein. Numeral 7 represents an arcuate closure plate for closing substantially the pocket 6, leaving just sufficient opening at the top and bottom thereof to permit the side portions 35 of the semi-circular shaped spring 8 to protrude therethrough. Numeral 9 represents a head portion of the fuse which is corrugated suitably at its periphery, this head portion having a window 10 and being secured to the body 5 by a screw 11. An elongated screw 12 not only extends through 40 the head 9 but also through the closure plate 7 and into the inner end portion of the body 5 so that through the use of this screw 12 both the closure plate 7 and the head 9 are retained to the body 5.

45 In the pocket 6 the end portions of the spring 8 are secured by rivets 13 to the inner end portion of the body 5. Numeral 14 represents a pin having a head for maintaining the spring 15 secured to the inner end of the body 5, this pin 14 extending inwardly to the pocket 6 where it is equipped with a substantially square shaped frame 15a having a slot 16 in the end thereof for receiving the fusible element 17. The intermediate portion of the spring 8 is also provided with a slot 18. It will be observed in Figure 7 that the fusible element 17 is provided with head portions 19—19 each longitudinal edge portion of which

is provided with a notch 20 defining a T-portion 21. These T-portions are disposed through the slots 16—18 and the fuse rotated so that the fuse will assume the position as shown in Figure 5 in which position, the fusible element will 5 retain the spring 8 under tension in the contracted position shown in Figure 5 so that the struck-out bosses 22—22 project beyond the periphery of the body 5 and engage into the threads of the socket 23, as in the manner shown in Figure 1. The socket 23 has a connection to the binding post 24. The frame 15a is connected to the contact 25 and this contact 25 in the socket is connected by the conductor 26 to the binding post 27.

10 It can now be seen, that when the fuse 17 blows, the spring 8 will be released thus pulling in the boss members 22—22 and freeing the plug from the screw socket 23 so that the spring 15 which has been under tension will throw the plug out 15 of the socket.

20 While the foregoing specification sets forth the invention in specific terms, it is to be understood that numerous changes in the shape, size and materials may be resorted to without departing from the spirit and scope of the invention as 25 claimed hereinafter.

Having thus described the invention, what is claimed as new is:

30 1. A fuse plug comprising a di-electric body having a pocket therein, a current conductive semi-circular spring having its ends secured to the body in the pocket, a fusible element, a contact spring secured to the body, a slotted member in the pocket to which the contact is secured, said semi-circular spring being provided with a slot therein, said fusible element being provided with a key head at each end for engagement to the slotted member and the slotted portion of the 35 semi-circular spring, said semi-circular spring when engaged by the fusible element is retained in a contracted position so that portions thereof protrude outwardly of the pocket at opposite sides of the body to engage with the threads of a fuse 40 socket.

45 2. A fuse plug comprising a body of dielectric material, a compressible spring contact at one end of the body, a pair of thread engaging members mounted on the body and normally projecting beyond the outside thereof, a fuse element, said fuse element being constructed and arranged to connect the compressible spring with the thread engaging members and to simultaneously retain said thread engaging members in thread engaging position, said thread engaging members being of 50 spring material and adapted to contract to the body when the fuse element ruptures.

55 MILO M. CULBERT.
